UNITED STATES PATENT OFFICE

2,464,796

BRICK CLEANING AND SHAPING MACHINE

Russell B. Cushman, Brattleboro, Vt.

Application November 19, 1946, Serial No. 710,862

1. Claim. (Cl. 51—109)

1.

This invention relates to a brick cleaning and shaping machine, the general object of the invention being to provide a wheel formed of emery, Carborundum or the like rotatably supported and arranged in a casing with guide means for holding the bricks in proper position against the wheel and means for rotating the wheel.

Another object of the invention is to provide blades on the wheel for blowing the dust from the casing and with means for adjusting the wheel to take up wear.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevational view of the apparatus with parts in section.

Figure 2 is an end view of the apparatus.

Figure 3 is a top plan view thereof.

Figure 4 is a section on the line 4—4 of Figure 1.

Figure 5 is a section on the line 5—5 of Figure 4.

Figure 6 is a top plan view of the wheel supporting cylinder.

Figure 7 is a view of one of the fan blades.

In these views the letter F indicates a supporting frame which includes the pair of base members 1, uprights 2, longitudinal beams 3 and braces 4. A horizontal casing 5 is supported at the top of the frame by the uprights 6 connected with the beams 3. The top of the casing has an opening 7 therein and a spout 8 extends tangentially from the casing and has the hooks 9 thereon for holding a bag or the like in position for receiving the dust and dirt from the casing as will be hereinafter described. A cylinder 10 extends upwardly through a hole 11 in the bottom of the casing and has the upwardly extending bolt 12 connected with its upper end, and a disk or wheel forming member 13 is fastened to the top of the cylinder by these bolts and their nuts 14. A ring-shaped member 15 of emery, Carborundum or the like is fastened by the disks 16 to the member 13, and blade forming members 17 are connected with the upper and lower faces of the member 13, these members 17 being preferably of the shape shown in Figure 7 and they form an air blast in the casing which will pass

2.

through the spout or chute 8 into a bag or the like covering the outer end of the chute and held thereon by the hooks 9. An angle bar 18 extends across the top of the casing and projects across a part of the opening 7, and an upright member of angle shape in cross section extends upwardly from the top of the casing as shown at 19, these parts forming guiding means for holding a brick in position with a part thereof extending into the casing to be engaged by the abrasive member 15. A pulley 20 is connected with the lower part of the cylinder 10 and has a plurality of V-shaped grooves 21 therein for receiving V-shaped belts 22 which pass over a similar pulley 23 on the shaft of a motor M which is supported on a platform 24 mounted on the frame. A bolt 25 threaded through a part of a bracket 26 on the platform is used to move the motor in a direction to tighten the belts. Thus the motor will 20 drive the cylinder to rotate the member 13 and the abrasive member 15. A shaft 27 is supported in vertical position in a part of the frame and passes into the cylinder 10 and anti-friction means 28 is provided between the shaft and the cylinder. The lower end of the shaft 27 extends into a U-shaped member 29 depending from a part of the frame and having slots therein through which a pin 30 passes. The pin 30 also passes through the lower end of the shaft 27 so as 30 to prevent rotary movement of the shaft. A set screw 31 is threaded in a hole in the member 29 engaging the bottom of the shaft so that by adjusting the set screw the shaft can be raised and lowered to raise and lower the cylinder 10 and the parts carried thereby. A lock nut 32 is provided for holding the screw 31 in adjusted position.

A fence-like guard 33 is attached to the frame and covers the belts 22 and the pulley 23 to prevent injury to the operator from these parts and to prevent objects from falling on the belts or pulley 23 to injure the same.

Thus it will be seen that when the motor is 45 in operation the cylinder 10 will be rotated so as to impart rotary movement to the members 13 and 15 so that the member 15 will clean mortar and the like from bricks held in contact with its upper face, and the dirt and foreign matter removed from the bricks will be blown from the casing by means of the blades 17 into a sack supported on the spout 8. By turning the screw 31 the parts can be adjusted to take up wear. The device can be used for squaring up bricks and to 55 give bricks any desired contour, such as rounding

the edges or beveling or shaping the brick to any desired form.

This apparatus will clean and shape bricks with practically no breakage and it greatly reduces the cost of salvaging old bricks for reuse.

It is thought from the foregoing description that the advantages and novel features of the invention will be readily apparent.

It is to be understood that changes may be made in the construction and in the combination and arrangement of the several parts provided that such changes fall within the scope of the appended claim.

Having described the invention, what is claimed as new is:

A brick cleaning and shaping machine comprising a horizontally elongated supporting frame, a circular casing rigidly horizontally mounted upon and disposed above the top of said frame intermediate the ends of the latter, said casing having an angular opening in the top and adjacent a side thereof for insertion therethrough of bricks to be cleaned or shaped, and being provided with a tangential discharge spout which extends horizontally beyond one end of the frame, means for holding the mouth of a dust collection bag over the outlet end of said spout, coaxing horizontal and vertical brick guides mounted on said casing at a corner of said opening, a vertical shaft mounted in the top of and projecting upwardly from said frame, a horizontal combined abrading ring and fan disk disposed within the housing and journaled on the upper portion of

said shaft, a motor mounted on one side and at the other end of said frame, belt gearing between the motor and said combined abrading ring and fan disk, and a guard mounted on the frame and extending over the belt gearing from the motor to the casing.

RUSSELL B. CUSHMAN.
